WALL TILE PANEL

David Lansky, Scarsdale, N.Y., assignor to Bentley Products Inc., New York, N.Y., a corporation of New York

Filed Feb. 25, 1965, Ser. No. 83,973

Term of patent 14 years

(Cl. D18—2)

FIG. 1 is an elevation of a wall tile panel, showing my design;

FIG. 2 is an edge view looking toward the lower edge as seen in FIG. 1; and

FIG. 3 is a section taken on the line 3—3 of FIG. 1. I claim:

The ornamental design for a wall tile panel, substantially as shown.
